UNITED STATES PATENT OFFICE.

JULIUS H. MARQUARDT, OF LOMBARD, ILLINOIS.

COMBINED SPARK-PLUG HOLDER AND TESTER.

1,383,476.

Specification of Letters Patent.

Patented July 5, 1921.

Application filed May 8, 1920. Serial No. 379,881.

To all whom it may concern:

Be it known that I, JULIUS H. MARQUARDT, a citizen of the United States, and a resident of Lombard, in the county of DuPage and State of Illinois, have invented certain new and useful Improvements in Combined Spark-Plug Holders and Testers; and I do hereby declare that the following is a full, clear, and exact description thereof, reference being had to the accompanying drawings, and to the characters of reference marked thereon, which form a part of this specification.

This invention relates to a novel spark plug tester and carrier for use on explosion engines of that type embodying in its ignition system spark or ignition plugs that are electrically operated to fire the compressed gaseous fuel in the engine cylinders, and relates more particularly to a novel device that is grounded on one side of the ignition circuit and is at the same time securely fastened to a fixed part of the motor, so that thereby the device, which may be termed a rack, may be securely fixed to a part of the motor which is adjacent to the spark plugs in their operative positions and, therefore, readily accessible to the normal spark plug positions to enable plugs to be readily removed from the cylinders and placed on the rack and vice versa, and which also, by reason of its grounded connection with one side of the ignition circuit through the engine frame, furnishes means to support a spark plug or plugs, so that the same may be tested for faults before being applied to the cylinders.

It is the experience of users of explosion engines, and particularly explosion engines used on motor driven vehicles that spark or ignition plugs are commonly carried in receptacles such as tool boxes, bags, and the like, where the parts thereof that need to be delicately adjusted are subject to mal-adjustment and where the porcelain parts are subject to checks, so that, in the experience of the average motor driven vehicle driver, the defects in spark plugs have been found to be largely due to the fact that no special place is provided to safely carry the same against the adverse conditions mentioned. Therefore, in many instances a new spark plug becomes defective or mal-adjusted before it has ever been applied to the engine cylinder. It is also the experience of motor driven vehicle drivers that the testing of plugs

merely by grounding a loosely held plug on the engine frame is inconvenient, requires considerable time, and is uncertain.

The principal object of the invention is to provide a device which will embody the double function of supporting the spark plugs adjacent to their places of use on the engine and in such manner that they may be readily tested when carried by said support.

I have shown in the drawings one known type of explosion motor (the Ford type) to which my invention is applied, and it is understood that when adapting it to other types of explosion motors, the device may assume structurally different forms and different dimensions while retaining all the advantages ascribed thereto in the illustrative embodiment herein shown.

As shown in the drawings,

Figure 1 is a side view of an explosion motor, showing in side elevation my novel spark plug carrier and tester.

Fig. 2 is a plan view of the principal parts shown in Fig. 1.

Fig. 3 is a perspective view of the holder detached from the other parts.

As shown in the drawings, 10 designates the engine casing or housing, which, in known forms of explosion motors, constitutes the ground for one side of the ignition circuit, the spark plugs being grounded thereto by direct contact with the metal part of the frame or housing.

11 designates as a whole the combined tester and holder. As herein shown, it takes the general form of an inverted U, embracing a holder member 12, down-turned legs 13, 13, and outwardly extending feet 14, 14, generally at right angles to the legs and in planes parallel to the holder portion 12.

The said holder portion 12 is pierced with a series of openings 15, which openings are threaded and said openings are of a diameter and the threads are so cut as to receive and properly engage the standard threads of the spark plugs 16, the spark plugs engaging the threaded openings 15 in the manner that they engage the threaded openings in 105 the cylinder walls of the motor.

In the type of engine herein shown, there are a number of symmetrically disposed tap or other bolts 17 which hold the parts of the engine casing together, and with this type of motor it becomes practicable to make the combined holder and tester rack of such

length that bolt openings 18 in the feet 14 of the rack register with the bolts 17, so that the rack may be fastened to the engine structure by standard means ready at hand and without the necessity of providing other means than the holder or rack such as is shown in Fig. 3. The said holder or rack is made of a good conducting metal, and is in contact with the engine frame or casing, so that it is included in the grounded side of the ignition circuit.

With this construction shown, it will be observed that the said combined holder and tester can be located closely adjacent to the spark plugs when in their normal or operating positions, so that when it becomes necessary to remove a defective plug a perfect plug is ready at hand to be quickly unscrewed from the rack or holder and applied to the engine cylinder, it being convenient to temporarily place the defective and removed plug into the holder for the purpose of carrying the same. It will also be observed, by reason of the fact that said holder or rack is included in one side of the ignition circuit, it becomes practicable to readily test a spark or ignition plug when supported in the rack by merely applying a contact to the proper part of the plug, which contact is connected with the other side of the circuit. This operation can be readily effected by one hand of the person testing or replacing the plugs, and by reason of the fact that the plugs are securely held in position during such testing, much time is saved and the accuracy of the test is certain.

While the rack or holder is shown as in-

serted into one side of the ignition circuit by being attached to the grounded side, embodying the engine casing, it will be understood that if neither side of said circuit be grounded, the said holder or rack may be otherwise included in one side of the ignition circuit.

I claim as my invention:

1. A combined spark plug carrier and test rack, embracing a current conducting member provided with a series of through openings to receive the threaded portions of the spark plug, and means whereby said carrier is adapted to be normally fastened to an engine case to be thereby inserted in one side of the ignition circuit of an explosion motor.

2. A combined spark plug carrier and test rack, comprising a current conducting member provided with a plurality of spaced threaded openings, and formed at its ends with integral downturned attaching feet that are adapted to rest on and to be secured to the frame of an explosion motor.

3. In combination with an explosion motor and its spark plugs, of a combined current conducting carrier and tester for spark plugs fixed to the grounded engine housing adjacent to the normal operating positions of the spark plugs, and provided with a series of spaced, threaded openings adapted to receive the threaded portions of the spark plugs.

In witness whereof I claim the foregoing as my invention, I hereunto append my signature this 5th day of May, 1920.

JULIUS H. MARQUARDT.
